UNITED STATES PATENT OFFICE.

JOHN HENRY TURNER, OF ABINGDON, ENGLAND.

NON-SLIPPING ATTACHMENT FOR THE SOLES AND HEELS OF BOOTS AND SHOES.

1,162,620.

Specification of Letters Patent. Patented May 9, 1916.

Application filed July 8, 1914. Serial No. 348,602.

To all whom it may concern:

Be it known that I, JOHN HENRY TURNER, a subject of the King of Great Britain, residing at Frilford Heath, Abingdon, Berkshire, England, have invented certain new and useful Improvements in Non-Slipping Attachments for the Soles and Heels of Boots and Shoes, of which the following is a specification.

This invention relates to the soles and heels of boots and shoes, whether for ordinary wear, or for use in playing games, or for sporting use generally, the object being to provide a very efficient preventive against slipping, as well as facilities for effecting repairs.

I am aware that it has heretofore been proposed to provide pads of rubber or the like which are secured to the sole by means of a plate of leather or the like, or by strips of leather or the like, inserted in depressions or channels formed in the rubber or the like, the rubber or the like being impinged between the plate or strip of leather and the sole; and I do not claim such broadly as my invention, the object of which is to provide an attachment which is light and durable, can be applied to any part of the sole where desired, can be readily repaired, and can be sold in the form of a plain strip adapted to be cut up into sections and fitted to any part of the sole of a boot or shoe of any size, thus obviating the necessity of employing numerous molds of different shape and size.

The invention consists essentially in providing raised portions or members—adapted to be secured to the sole or heel as usual—composed of sections adapted to be applied to any portion of the sole each section consisting of pieces of substance or material of different characters or natures which are fashioned and assembled in such manner that one piece, when fastened in place, serves to secure the complementary piece or pieces.

In the accompanying drawings, which illustrate some forms of the invention:— Figure 1 is a plan of a strip constructed in accordance with this invention. Fig. 2 is a cross section of Fig. 1; Fig. 3 is a plan view of another form of the strip; Fig. 4 is a cross section of Fig. 3; Fig. 5 is a plan view of a toe piece; Fig. 6 is a plan view of a heel piece; and Figs. 7, 8, 9 and 10

illustrate some of the methods of applying the attachment to the soles and heels of boots and shoes.

The strip shown in Figs. 1 and 2 consists of a channel-shaped member 1 composed of rubber or other suitable material or substance, and a strip 2 of leather, fiber or other suitable substance or material which serves as a fixing medium through which brads, rivets, screws or the like fastening means 3 may be driven to secure the device to the sole, the fastening means passing through the bottom of the channel-shaped member 1 and into the sole.

In Figs. 2 and 4 is shown a strip consisting of the channel-shaped member 1, the strip 2 and an additional strip 4 of wire or the like, which form of the device can conveniently be secured to the sole by staples 5. Obviously this wise securing means can be adopted in the arrangement shown in Fig. 1 instead of the brads 3 therein shown. The strip 2 is preferably formed with a groove 6 to receive the strip 4 so that the latter does not project beyond the face of the device. If desired either or both of the members 1 and 2 may be made up of two or more different materials. For instance, the member 1 may consist of a canvas base with a channel-shaped rubber strip secured thereto, as shown in Fig. 4.

Fig. 5 illustrates a strip bent to conform to the shape of the toe of the sole, and Fig. 6 illustrates a strip bent to conform to the shape of a heel. If desired, the sides of the channel-shaped member may be merged together at either or both ends as shown at 7, and also at intermediate points as shown at 8 (Fig. 1) to keep the sides from being distended.

In use, a section is secured to any part of the sole of a boot or shoe, where desired, by brads, rivets, screws, staples or any other suitable fastening means which are driven through the member 2, the base of the member 1 and into the sole, the member 2 serving to hold the fastening means and prevent the member 1 from being injured thereby. The device is suitably applied in sections so that those sections which receive the most wear can be readily removed and replaced by new sections, but if preferred, it may be applied originally in one piece and the worn part subsequently cut out and

replaced by a new section. The outer faces of the edges of the member 1 preferably project slightly beyond the outer faces of the member 2 but if desired the outer face of the member 2 may be arranged to coöperate with the outer face of the member 1 to grip the ground and to save the edges of the latter from being broken away.

In Fig. 7 is shown the sole of a boot to which is applied a toe piece and a heel piece bent to the form illustrated in Figs. 5 and 6, strips secured around the edge of the sole and a longitudinal strip secured along the middle of the sole, which arrangement has been found very suitable for golf shoes.

In Fig. 8 is shown a toe piece, a heel piece and two V-shaped bars, one consisting of two sections and the other of a strip bent to the desired shape. This arrangement is very suitable for walking shoes.

In Fig. 9 is shown a toe piece, a heel piece and a series of cross-bars suitable for football boots.

In Fig. 10 is shown a continuous strip bent and secured entirely around the sole, and a similar strip, though preferably stronger, bent and secured around the heel.

It will be readily understood that a worn part of a continuous strip may be cut off, removed and replaced by a new section, or the strip may be applied in sections and any

worn section subsequently removed and replaced by a new section.

Having thus described my invention what I claim is:—

1. A new article of manufacture, comprising a non-slipping attachment for the soles of boots and shoes, having a channel-shaped member of non-slipping material, a second member fitting within said channel and formed with a longitudinal groove and a length of wire fitting within said longitudinal groove.

2. In non-slipping attachments for the flexible soles of boots and shoes, a rectangular frictional strip of rubber able to easily conform during use without buckling or set to deformation in and out of its own plane, of indeterminate length, capable of being cut into sections, each section comprising a channel, and a complementary locking portion pliable out of its own plane fitting within said channel, constructed and arranged to receive means for securing said sectional strip to whatever character of bending surface desired, and a securing means for said sectional strip.

JOHN HENRY TURNER.
